CLAIM

The ornamental design for a fire-resistant flap, as shown and described.

DESCRIPTION

FIG. 1 is a front perspective view of a fire-resistant flap ("flap") showing my new design;

FIG. 2 is another front perspective view thereof, shown with hook-and-loop fastener in the open position;

FIG. 3 is a front plan view thereof;

FIG. 4 is another front plan view thereof, shown with hook-and-loop fastener in the open position;

FIG. 5 is a left side view thereof, shown with hook-and-loop fastener in the open position;

FIG. 6 is a top view thereof, shown with hook-and-loop fastener in the open position; and,

FIG. 7 is a front plan view thereof with the flap shown in the open position.

The hook and loop portion of the claim forms no part of the claimed design. The small broken lines shown within the flap depict stitching and form no part of the claimed invention. The broken lines that form the coat depict the environment and form no part of the claimed design.
